Amelius V. Pitts

UNITED STATES PATENT OFFICE.

AURELIUS V. PITTS, OF MARSEILLES, ILLINOIS.

ELEVATOR-CASE.

SPECIFICATION forming part of Letters Patent No. 414,721, dated November 12, 1889.

Application filed August 27, 1888. Serial No. 283,947. (No model.)

To all whom it may concern:

Be it known that I, AURELIUS V. PITTS, a citizen of the United States of America, residing at Marseilles, in the county of La Salle and State of Illinois, have invented certain new and useful Improvements in Elevator-Cases, of which the following is a specification, reference being had therein to the accompanying drawings and the letters and figures of reference thereon, forming a part of this specification, in which—

Figures 1 and 3 are side views of the jointed portion of the elevator-case, showing it both in its folded and extended positions; and Fig. 2 is a perspective view of the jointed portion of the elevator-case to more clearly show its construction.

This elevator-case is more particularly designed for use on a grain-separator, where it is necessary to reduce the height of the elevator to permit the separator to pass under obstructions—such as low doors, gates, trees, &c.

Referring to the drawings, A B represent the elevator-case. In order to form its joint so it can be let down at the top or folded, as shown in Fig. 1, a triangular-shaped cut is made in one side to remove a portion of the form shown at *r*, the lower part of which is hinged to the lower part B of the elevator-case by means of hinges *W*, and forms a door to close said opening when the part A of the elevator-case is upright and in line with the lower part B, as shown in Fig. 3. A button *N* or any other suitable fastening may be used to hold said door in the position shown in said figure, which button, for convenience, is omitted in Fig. 1. Said triangular-shaped cut or opening has its apex extended beyond the center line of the case, or about three-fourths the way across, and the two parts A B of the case are severed or separated from each other from the apex of said triangular cut or opening to and on a line at right angles with the opposite side of the case.

The two parts A B of the case are connected at each side at the apex of said opening by means of hinges *S*, in such manner that a

joint is formed in the case, so that its upper part A may be let down or folded to be at 5° right angles with the lower part B, as shown in Fig. 1.

When the part A of the case stands in a vertical position, as shown in Fig. 3, the door *r* is turned up and secured closed to supply 55 the portion cut out of the side of the case, and make it the same as if no such opening had been cut in its side, and at such time the two parts of the case are held rigidly in the position shown in Fig. 3 by means of the bolt 6c or screw *O*, connecting the integral projecting lugs *c* on said hinges.

In Fig. 1 the case is represented as folded down, so that its two parts are at right angles with each other. When so folded, a triangular-shaped opening is made between the two parts A B, on their opposite side from the opening having door *r*. This opposite opening is provided with the door *a*, formed to fit it, which door is hinged to part B by means of 7c the hinges *z*, as shown, and in a similar manner to that in which door *r* is hinged to said part. In this case, as the invention relates entirely to the construction of the elevator-case, no elevator chains or buckets are shown. The 75 hinges *S* are located at the place shown, so that when folded the parts within the case may not be injured.

Having thus described my invention, what I claim as new, and desire to secure by Letters 80 Patent, is as follows, to wit:

1. The elevator-case shown and described, consisting of the two parts A and B, hinged together at the apex of a triangular opening between said parts, in combination with the 85 hinges *S*, having the opposite side lugs *c*, bolt *O*, and the triangular-shaped doors *r* and *a*, substantially as and for the purpose set forth.

2. The combination of the elevator-case A B, hinges *S*, and doors *a* and *r*, substantially 90 as and for the purpose set forth.

AURELIUS V. PITTS.
